UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

AUTOMATIC VALVE.

1,167,815.

Specification of Letters Patent. Patented Jan. 11, 1916.

Application filed May 16, 1913. Serial No. 768,059.

To all whom it may concern:

Be it known that I, EDWARD E. GOLD, a citizen of the United States, residing in the borough of Manhattan, city, county, and State of New York, have invented certain new and useful Improvements in Automatic Valves, of which the following is a specification.

My invention relates to an automatic valve which is particularly adapted for use in controlling the supply of steam to a steam heating radiator.

My invention has for its object to provide a valve which will automatically control the supply of heating fluid to a heater and which is adapted to be automatically operated by a thermostat in accordance with the temperature conditions in the apartment to be heated.

In effectuating this object my invention consists in the provision of a magnetically operated valve which is specially adapted for application to a steam heating system, and which is adapted for use in connection with a thermostat whereby the same is operated in accordance with the temperature in the said apartment.

My invention in one adaptation thereof is illustrated in the accompanying drawings, wherein—

Figure 1 is a perspective view partly in section of an apartment having a steam heating apparatus equipped with my invention. Fig. 2 is an enlarged vertical detail section of my invention applied to a steam heating pipe.

I have illustrated my invention as applied to a car, wherein steam is supplied from the train-pipe A and is conducted through the branch B which passes through the floor C of the car to a radiator D. A hand valve E is represented as being applied to the pipe B for the purpose of shutting down the supply of steam when desired. The exhaust from the radiator is discharged through a vertical trap which may have the usual thermostatically controlled outlet F situated below the floor of the car, and the usual blow-off valve G. At a suitable point in the pipe, as for instance in the inlet pipe, is situated the means for controlling the heater, and in this case these means are adapted to control the supply of steam to the

heater, although they might equally well be adapted to control the outlet from the heater. 55

In the form in which I have shown my invention an admission valve H is contained within a casing I and controls the supply of steam to the radiator. The means for automatically controlling the movements of this 60 valve include a magnet which as a whole I designate J. The said magnet, illustrated in detail in Fig. 2, has the usual coil K surrounded by an iron casing L, and the center of the magnet, which is hollow, receives a 65 tube M which, at its upper end, is threaded steam-tight to an upper iron ring N, which is also threaded into the outer casing L. This ring N is provided with recesses n by which it may be removed from its position 70 when desired. The valve stem is formed in two parts O, O¹, which are separated at a median point o¹ as illustrated. The lower part O of this valve stem is pinned by pin o to a spring cap P, and between this spring 75 cap P and the valve seat Q is coiled spring R, which normally holds the valve H in its upper or open position. The upper part O¹ of the valve stem is threaded into the armature bar S, and is adjustably supported 80 thereon by means of the nut s, which is threaded on the end of said valve stem. A bonnet T is threaded onto the upper part of the casing L and has a steam-tight connection therewith so as to prevent the leakage 85 of steam at this point.

Means for shutting down the valve H when desired are provided, and the same include a bolt U which is threaded into the upper part of the bonnet T, and at the 90 lower end has a cone valve u which bears against a correspondingly shaped seat in the bonnet, and provides means for preventing the escape of steam from the chamber when the bolt U is retracted. Additional 95 means for preventing the escape of steam are provided consisting of a stuffing-box u¹. A bonnet V provides means for connecting the tube M with the casing I of the steam pipe. For this purpose the said bonnet V 100 is preferably provided with a depending threaded sleeve v, which is threaded into a corresponding flange w on the casing. A suitable stop, such as the flange v¹ limits the downward movement of the bonnet V. 105 The tube M is threaded on its lower exterior

portion and screwed into the bonnet V. This tube has a small shoulder m at the upper end of the threaded portion. This shoulder m together with the stop v^1 provide 5 the means whereby the adjustment of the magnet relative to the valve is maintained constant. For ease in taking the apparatus apart, as for instance, for the purpose of repair or replacement of any of the parts, 10 I separate the valve stem into two parts O O^1 as illustrated, and this separation, which is illustrated at o^1 , enables the two parts to abut against one another so that the spring R shall move the upper part and 15 the armature, and likewise that the movements of the armature shall move the valve H. At the same time the tube M may be easily removed by unscrewing from the bonnet V, whereupon the stem will separate 20 at o .

The valve proper is of usual construction and has a wearing face h , the nature of which will be determined by the pressure to which it is to be subjected, and the attachment to the valve stem is in the usual 25 manner.

Means are provided whereby the magnet J is energized for the purpose of controlling the supply of steam, and these means, as 30 illustrated, accomplish their object by causing the magnet to close the valve H when the temperature in the apartment rises to a previously determined point. The magnet is included in an electric circuit X, 35 which contains a source of electricity Y and a switch x . Also included in this circuit is a thermostat Z, which may be of any desired construction, and as many constructions of thermostat are available for this 40 purpose I have not thought it necessary to illustrate the same in detail. This thermostat is adapted to open or close the electric circuit upon a change of the temperature in the apartment, and a switch x enables 45 the circuit to be permanently opened or closed.

In the operation of my apparatus in the form in which the same is illustrated, when 50 the temperature in the apartment rises to the predetermined point, the thermostat Z will close the circuit X and energize the magnet J causing the armature S to be attracted, thereby depressing the stem O^1 O, and closing the valve H shutting off the 55 supply of steam. When the temperature in the apartment falls a sufficient amount the thermostat Z opens the electric circuit X, whereupon the spring R pressing against the spring plate P will lift the valve stem 60 and raise the armature. Steam will then be permitted to flow through the steam pipes in the direction of the arrows.

When steam is being admitted to the 65 radiator D it will leak around the valve stem and into the armature chamber. For

the purpose, therefore, of preventing the escape of steam from the said armature chamber into the coils, I cause the tube M and the bonnet T to be steam-tight, and the ring N likewise has a steam-tight fit, whereby the steam is prevented from escaping from the armature chamber or the tube. When it is desired to permanently shut off steam, the screw bolt U may be screwed down until its face u depresses the valve stem sufficiently to close the valve. The stuffing-box u^1 will prevent leakage of steam past the said screw bolt. 75

The adjusting nut s enables the height of the valve stem O^1 to be adjusted relatively 80 to the armature S so as to at all times obtain a tight closing of the valve H.

I have illustrated in the accompanying drawing the preferred form for my invention which is the best form now known to me, and this has been carefully described, but I do not desire to be understood that I intend my invention to be limited strictly to all the details of construction therein illustrated and described, as the same may 85 be varied and equivalent devices employed 90 within the limits of the appended claims without departing from my invention.

I claim as my invention:—

1. A valve, a valve seat, a valve casing, a spring tending to press said valve away from its seat, an actuating magnet adapted when energized to seat said valve, a casing inclosing the armature thereof and forming fluid-tight chamber therefor, a valve stem 100 connecting said valve to the armature, a tube having one end opening into the said chamber and the other end connected to the said valve casing, and providing a free passageway for said valve stem, said tube 105 adapted to be disconnected from said valve casing, and said valve stem being divided transversely within said tube into disconnected parts capable of movement relative to each other and that part of said stem which 110 is attached to the valve being adapted to slide out of said tube upon removal of the tube from the valve casing.

2. A valve casing, a valve disk therein, spring means for normally holding said 115 valve open, valve operating means comprising a magnet, a fluid-tight casing for its coil, a bonnet fitted to one end thereof and inclosing an armature chamber, said magnet having a passage therethrough leading to 120 said chamber, and a tube extending through said passage and connected to said casing, said armature chamber and said connected passage being fluid-tight, a bolt threaded in said bonnet and having a cone valve on its 125 inner end, a seat therefor in said bonnet adapted to be engaged by said bolt to prevent the escape of fluid, said bolt having a smooth portion and a stuffing-box on said bonnet therefor and adapted when moved 130

to extreme open position to close said valve disk against the passage of steam, and when closed to permit said valve disk to open and to close the passage in the bonnet against 5 leakage of steam.

3. A valve, a valve seat, a spring tending to press said valve away from its seat, an operating magnet adapted when energized to seat said valve, having a coil and an armature, a casing therefor forming a fluid-tight covering for said coil and a bonnet attached to the top of said casing providing a chamber for said armature, a tube connecting said valve and said armature chamber and capable of being disconnected from said valve, a valve stem adapted to move freely in said tube and being divided transversely therein into disconnected parts, connected respectively to said armature and to said valve 20 whereby upon removal of the tube from the valve said stem will separate, said tube and armature chamber being fluid-tight, and means for adjusting the stem relatively to the armature.

25 4. A valve, a valve seat, a valve casing, a spring tending to press said valve away from its seat, an actuating magnet adapted when energized to seat said valve, a casing inclosing the armature thereof and forming a fluid-tight chamber therefor, a valve stem connecting said valve to the armature, a tube connecting said chamber with the valve casing and disconnectible from said casing, and providing a free passageway for said valve 30 stem, said valve stem having an adjustable connection to said armature whereby the position of the valve relatively to its seat may be adjusted to compensate for wear, and being divided transversely within said 35 tube, into disconnected parts capable of separating to permit the removal of said tube.

40 5. A valve having a valve disk, a valve

seat and a valve casing, a bonnet threaded thereon and having a shouldered engagement therewith, an operating magnet having a coil and an armature, a casing for said magnet comprising an integral tube threaded to said bonnet and having a shouldered engagement therewith and extending within the said coil, and a shell inclosing 45 said coil and supported on said tube, a bonnet on said shell secured steam-tight thereto, and extending beyond the outer end of said tube and providing a space for the movement of said armature, a valve stem located 50 in said tube and secured to the armature and to the valve disk, and a spring tending to press said valve disk in a direction opposed to said magnet.

6. A valve, a casing therefor, a bonnet on 55 said casing, a valve disk in said casing and operating means for said valve comprising a magnet, a shell surrounding the coil thereof, a tube extending inside of the coil and having a shouldered engagement with said 60 bonnet, a closure extending from the bottom of the shell to the tube, a steam-tight closure between the upper end of the shell and the tube, a bonnet secured steam tight to the shell and providing an armature chamber, 65 a valve stem extending from said chamber through the bonnet of the valve casing and connected to the valve disk, an armature in said chamber adjustably connected to said stem, a bolt adjustably threaded in the bonnet over said armature, a cone valve on said bolt, and a seat therefor in said bonnet.

In witness whereof, I have hereunto signed my name in the presence of two subscribing witnesses.

EDWARD E. GOLD.
